UNITED STATES PATENT OFFICE.

FREDERICK LEWIS McMULLEN, OF MILWAUKEE, WISCONSIN.

PANTS OR TROUSERS CONSTRUCTION.

Application filed July 26, 1926. Serial No. 124,942.

This invention relates to garments, particularly to pants or trousers, and has for its object the provision of a construction embodying a novel closed or corded seat seam and waist band connection, together with the method of producing the same, the arrangement and method of formation being such that alterations in the size of the waist and seat may be effected with the minimum labor.

10 It is well known in the art that there are two types of seams used in the formation of the seat portions of pants or trousers, namely, the open seam and the closed seam. The former is made simply by superposing the two pieces of cloth or leg sections to be secured, stitching them along a single line, unfolding and then pressing down and back the marginal edges which project beyond the seam. This type is used only in the making

15 of dress trousers or those not subject to severe wear. The closed seam is the type used in the making of work trousers, overalls and the like, which are subjected to hard wear, and is the type employed in the present instance.

20 The closed seam may be considered as being corded or welted and quite naturally possesses a far greater degree of strength and resistance to strain than the open seam, facts which recommend the employment of this type in connection with work clothes.

25 It is also well known that the present method of making a closed or corded seat seam is such as to permit of alterations to increase the size, but the band provided is usually so arranged that it must either be ripped off and replaced with a larger one or it must be cut and an insert set or stitched therein, the insert consisting simply of an additional piece of banding. In case a reduction in size is

30 desired it is necessary to split the banding and to rip back on each side of the seam the amount necessary, subsequently to which the banding must be restitched. Obviously, the making of alterations either to increase or decrease the size of a garment embodying the ordinary closed seam and waist band connection requires considerable time and labor.

It is with the above facts in view that I have designed the present invention which has for a more specific object the provision of a seat seam of the closed type in combination with a split band readily capable of being lengthened or shortened in accordance with variations in the location of the seat seam necessitated by alterations in the size of the garment, it being unnecessary at any time

to replace the band or to rip it off from the leg sections, the labor of making alterations being consequently cut down to the minimum without in any way detracting from the strength of the garment.

To the attainment of the foregoing and other objects and advantages the invention preferably consists in the construction and arrangement of parts and the method steps to be hereinafter more fully described and claimed, and illustrated in the accompanying drawing, in which:—

Figure 1 is a fragmentary view of the inside of the waist portion of a pair of trousers, this view showing the marginal extensions of the leg sections separated at the seat seam and also showing one end of the split band folded back or into open position.

Figure 2 is a similar view with the free end of the split band in proper position with respect to the marginal extensions of the leg sections but not stitched down.

Figure 3 is a similar view showing the band stitched down in place.

Figure 4 is a view similar to Figure 3 showing the appearance after the garment has been altered to increase the size at the seat and waist.

Figure 5 is a view looking at the outside of the garment or the reverse side of that shown in Figure 4.

Referring more particularly to the drawings, the numerals 10 and 11 designate the two breadths or pieces of fabric for forming the rear portions of the leg sections of a pair of trousers, these pieces being united at the center of the back or at what is called the seat seam. In accordance with the present invention the upper edges of these pieces 10 and 11 are folded over inwardly upon themselves as shown at 12. A waist band section 13, preferably provided with a lining 14, is then placed against the inner face of surface of each of the sections 10 and 11, prior to their connection by the seat seam to be described, the edges of the band sections being turned in as indicated at 15, in the customary manner. The band sections are then united to the sections 10 and 11 by rows of stitching 16 near the upper and lower edges. The band on the leg section 11 may terminate flush with the edge of the fabric, whereas the band on the leg section 10 is of greater length to provide a free end portion 17 which projects beyond the edge of the fabric in the form of a tongue.

The two members or sections 10 and 11 are then arranged in superposed relation and united by a line of stitching 18, after which the pieces or sections are flattened out or extended into the position shown in Figure 1, the marginal portions beyond the lines of stitching lying together against one leg section. Subsequently to this, stitching is effected along a line 20 in spaced substantially parallel relation to the stitching 18. This produces what is known as a corded or closed seam designated in general by the numeral 21. The free end portion 17 of the band is then folded about the edges of the marginal extensions 19 of both sections 10 and 11 as shown in Figure 2, and the whole is then flattened down and secured by a line of stitching 22, as shown in Figure 3.

Whenever occasion arises to increase the size of the garment at the side and waist band, it is of course necessary to rip out the stitches 22 and also the lines of stitching 18 and 20, nothing else being required to effect disconnection of the pieces or sections 10 and 11 as well as the sections of the band. The sections 10 and 11 may then be moved apart to the desired extent, the marginal extensions 19 being of course decreased in width. The seam is then put in at the new position in exactly the same manner as above described.

Referring to Figure 4 the condition of the parts when the garment is thus enlarged is clearly indicated. In this figure the numerals 18^a, 20^a and 22^a designate the perforations left by the removal of the original lines of stitching 18, 20 and 22, and the reference characters 18^b, 20^b and 22^b designate the corresponding new lines of stitching.

Whenever it is desired to decrease the size of the garment, the same lines of stitching are ripped out and the sections 10 and 11 decreased by reserving or forming the seam farther back, the marginal extensions 19 being

of course then of greater width than before. It is quite apparent that it is absolutely unnecessary to detach the band sections from the leg sections 10 and 11 at any time and it is therefore obvious that the work of making alterations is simplified to the greatest possible extent.

While I have shown and described the preferred embodiment of the invention and a certain method of stitching, together with other specific details, it should of course be understood that I reserve the right to make all such changes in the arrangement, combination and stitching as will not depart from the spirit of the invention or the scope of the claim hereunto appended.

Having thus described the invention, I claim:

Pants or trousers construction embodying leg sections united at the back of the trousers by a seat seam formed of a plurality of lines of stitching passing through the leg sections at a distance from the edges thereof to provide marginal extensions folded back upon each other and lying against one of the leg sections, and waist band sections secured to the leg sections by said lines of stitching, one waist band section terminating flush with the edge of one marginal extension and the other having a free end portion to constitute a tongue projecting beyond the edge of the marginal extension of the section to which it is secured, said free end of the waist band section being folded over the edges of the marginal extensions and engaged between said extensions and the leg section against which they lie, and a line of stitching uniting the folded back marginal extensions and the underlying waist band extension to the leg section against which they lie.

In testimony, that I claim the foregoing as my own, I have hereto affixed my signature.

FREDERICK LEWIS McMULLEN.
